UNITED STATES PATENT OFFICE.

THEODORE H. FRENCH, OF WASHINGTON, PENNSYLVANIA.

BROOM.

Application filed September 6, 1924, Serial No. 736,305. Renewed August 20, 1927.

My invention relates to improvements in brooms, and particularly in brooms having removable handles. A broom with removable handle is advantageous for several reasons; one reason is that either the handle or the brush may be replaced when broken or worn out, without the necessity of discarding the whole; another reason is that the separated parts may be packed in quantity for shipment with substantial economy of cost and of space.

A broom embodying my invention is illustrated in the accompanying drawings. Fig. I is a view of the broom in side elevation; Fig. II is a fragmentary view to larger scale, in medial vertical section; Fig. III is a view in transverse section, on the plane indicated by the line III—III, Fig. II. Figs. IV, V, and VI are views in perspective of certain parts detached. The succession of these three figures on the sheet is in the order of assembly.

The broom structure includes essentially the brush 1, the handle 2, and the keeper 3. Additionally a shield 4 is conveniently included, which serves to conceal structural details and to present a better appearance, and to afford an advertising surface.

The brush 1 is of usual construction, consisting of a sewn sheaf of broom-corn, properly shaped and trimmed. The butt-end of the sheaf is however capped and encased in a metal shoe 11 (formed ordinarily of sheet steel), riveted to the sheaf as indicated at 12. A central orifice is formed in shoe 11, and surrounding this orifice is an inwardly extending, screw-threaded ferrule 13. This ferrule 13 is preferably formed as a separate piece with flanged base, by which it may be permanently united to the web of metal which forms the adjacent part of the shoe 11. The ferrule is preferably formed from sheet steel by stamping and thread-rolling. In Figs. II and VI an engagement of tongues 14 cut from and inturned from the substance of shoe 11 upon the edge of the base flange of ferrule 13, is shown. This is itself not preferably the effective means of union of these parts; it is merely the means of initial assembly, and is preferably followed by spot-welding between the surfaces so assembled in contact.

In the building of the brush a central space is left extending inward in the axial line of the ferrule 13 when applied, a space such as to allow the seated handle 2 (pres-

ently to be described) to extend through the ferrule and inward to the zone of sewing A, as indicated in Fig. II.

The butt-end of the brush, beneath the shoe 11, and the surfaces of broom-corn spread apart to form within the brush a space for the entrance of the handle as described, are in the course of fabrication, preferably coated with pitch.

The shoe 11 is split at its ends, as indicated at 15, Fig. VI, to allow it, normally collapsed, to spread and to come to snug engagement against the butt-end of the sheaf of broom-corn, and then to be riveted to place in such snug engagement.

The handle 2 of the broom is preferably formed of wood as is usual. It terminates in a long conical point. This point is preferably formed as or is encased within a separate piece, a ferrule 21 of suitable metal, such as aluminum. The continuity of the conical point of the handle is interrupted by a screw-threaded band, adapted to engage the screw-threaded ferrule 13, already described. Thus adjacent the screw-threaded band a tapered surface is found for purposes presently to be described. The construction in this particular is clearly shown in Fig. II. When the handle is in place and seated and secured by the screw-threaded engagement here alluded to, the pointed end of the handle will extend within the brush to the zone of sewing A. This inward extension of the handle within the brush affords strength, particularly strength to resist the strain of service.

The keeper 3, formed also, preferably, as a stamping of sheet steel, is shaped to fit snugly upon the shod butt-end of the brush, to be arched over the shoulders of the brush member leaving open spaces 33 on either side, and by its flaring ends 31 to make wedging engagement upon the sloping shoulders 16 of the brush. The keeper is provided with a central orifice around which the metal web of the keeper 3 is crowned, as is indicated in the upwardly curved tapering rim 32.

When the parts are assembled, as shown in Fig. II, the crown 32 which surrounds the orifice in the keeper is engaged by the conical surface of the ferrule 21 of the handle, and the screwing of the handle home places the keeper 3 under strain: the flaring ends 31 of the keeper engaging the sloping shoulders 16 of the brush, yieldingly resist

the strain which is exerted, by the screwing of the handle home, upon the crown 32 of the keeper. The strain thus set up holds the parts firmly in assembled position, prevents the loosening of the screwed-in handle, and strengthens the whole for service.

The shield 4 takes no essential part in the mechanical organization. It is merely an idle member applied upon the shod end of the brush 1, and interposed between the brush 1 and the keeper 3, and clamped to place beneath the keeper. The shield 4 consists merely of opposite plates united by bridging web or webs 41. It is freely expandible, to shape itself to the butt-end of the brush. Allowance is of course made in the proportioning of the other parts, for the presence of this shield member 4.

The shield member when in place covers and conceals the cheeks of the shoe 11, through which riveting has been made, and, exposed within the spaces 33 of the keeper, presents fair smooth surfaces at these points. These fair smooth surfaces are of course available for advertising purposes.

The exposed metal surfaces may be coated, colored, and decorated as desired.

I claim as my invention.

1. In a broom the combination of a brush member provided with sloping shoulders and with a screw-threaded bore extending inward from its butt-end, a handle provided at an interval from its tip with a screw-threaded band and, adjacent such band, with a tapered surface, and seated in the bore in the brush member, its screw-threaded band

engaging the screw thread of such bore, and its tip extending inward beyond such region of engagement and into the body of the brush member, and a keeper of spring metal with flaring ends and with medial and crowned orifice overlying the butt-end of the brush member and surrounding the tapered surface of the handle introduced within the bore of the brush member, and engaged at its crowned orifice by the handle and engaging at its ends and under tension the shoulders of the brush member while the handle, introduced into the bore within the brush member is remote from screwed-home position, said keeper, when the handle is screwed home in the brush member, being held under tension between surfaces which it engages upon the shoulders of the brush and upon the taper of the handle.

2. In a broom the combination of a brush member encased at its butt-end in a sheet-metal shoe riveted to place upon it, said shoe being provided with a screw-threaded bore, a screw-threaded handle removably seated in said bore, an arched keeper overlying the shoulders of the brush member and surrounding the handle when introduced in the bore of said brush member, and a shield interposed between the brush member and the keeper and overlying the riveted sides of the shoe, otherwise exposed within the arch of the keeper.

In testimony whereof I have hereunto set my hand.

THEODORE H. FRENCH.
